INHALER

Oliver J. Dufresne, St. Paul, Minn.

Continuation of application Serial No. 125,434, November 4, 1949. This application June 15, 1953, Serial No. 361,551

7 Claims. (Cl. 128—200)

My invention relates to an improvement in inhaler wherein it is desired to provide a simple construction which may be made at low cost and which is extremely efficient in operation.

In my previously filed application, Serial No. 89,929, filed April 27, 1949, now Patent No. 2,598,365, granted May 27, 1952, I described a cylindrical inhaler having a branched end designed to engage in both nostrils simultaneously. A screw cap was threaded on the end of the tubular receptacle and a valve device was provided internally of the body for simultaneously closing the passages through the branched end of the structure when the screw cap was in closed position.

It is an object of the present invention to provide a device capable of accomplishing somewhat the same purposes as described in my previous application, but to disclose a structure which is somewhat less costly to manufacture. As a result my device may be produced at low cost and may be sold inexpensively.

A feature of the present invention lies in the provision of a medicine compartment in which may be enclosed a volatile or odorless medicine, or similar material, which may be inhaled. The container for this material is closed with the exception of openings near opposite ends of the container. One opening at one end of the container is arranged to be closed by the portion of the device designed for engagement into the nostrils. The other of the openings at the other end of the enclosure is likewise designed to be closed by a portion of the body of the device designed for engagement in the nostrils. By moving the medicine compartment, which is an inner receptacle, relative to the body of the apparatus, both of the openings described may be simultaneously opened or closed.

A feature of the present invention lies in the provision of an inhaler comprising two relatively telescoping elements which may preferably move between two specified extreme positions. In one of these relative positions of the two telescoping members, the medicine compartment comprising one of the telescoping elements may be entirely sealed. In another relative position of the two elements, both ends of the medicine compartment are opened. As a result air may be drawn through the medicine compartment to carry the odor or fumes of the contained medicine.

A feature of the present invention lies in the simplicity with which the present device may be formed. The main body of the apparatus is in three parts, two of which are secured together to form the medicine compartment. The medicine compartment comprises a hollow body having an open end which is closed by a suitable cap. The cap is preferably permanently anchored to the body of the chamber and serves as a means of moving the chamber relative to the portion of the apparatus designed to engage in one or more of the nostrils.

A feature of the present invention lies in the fact that

2

a valve is provided on the body of the device designed to engage in one or more of the nostrils. This valve is designed to extend into or accommodate an opening in the medicine chamber. In one relative position of the two parts, the opening is closed by the valve while in another position thereof, the opening remains open.

One of the features of this invention lies in the particular shape of the inhaler. The body is of relatively large cross-sectional area, to accommodate a substantial quantity of medicament. The outer surface of the body tapers inwardly so that the nostril portions are spaced properly to extend into the nostrils of the user. The space between the nostril engaging portions is such as to permit the projecting portions to fit into any nose. By tapering the other sides of these portions, the portions may be inserted to the proper extent to snugly fit any nostril opening.

The present application is a continuation of my previously filed application, Serial No. 125,434, filed November 4, 1949, and now abandoned.

These and other objects and novel features of my invention will be more clearly and fully set forth in the following specification and claims.

In the drawings forming a part of my specification:

25 Figure 1 is a perspective view of my inhaler showing the construction thereof with the cap removed.

Figure 2 is a sectional view of the apparatus with the cap in place, but with the medicine chamber in open position.

30 Figure 3 is a cross sectional view through the apparatus, the position of the section being indicated by the line 3—3 of Figure 2.

The inhaler A includes two relatively slidable elements indicated in general by the numerals 10 and 11. A cap 35 which is indicated in general by the numeral 12 preferably frictionally engages an end of the part 11 and acts to enclose a portion of this part 11. The cap 12 is desirable as it acts as a protection for the nostril engaging end of the device and keeps this portion of the device clean. However, the cap 12 may be omitted if desired.

The part 10 of the device comprises a medicine chamber forming an inner receptacle which is designed to enclose a suitable medicine or similar material which is to be inhaled. In preferred form, the container 10 is partially filled with an absorbent body which has been impregnated with the medicine. The absorbent body is not shown in the drawings as it may be of any suitable size or shape, and the absorbent body is preferably sealed within the member 10.

50 The part 10 is shown as having a longitudinal wall 13 which may be oval in cross section as illustrated, or may be of other suitable cross sectional shape. The closure wall 14 acts to close the major portion of one end of the wall 13. The closure wall 14 is provided with a frusto-conical indentation 15 having an opening 16 therethrough.

A cap 17 is provided to close the other end of the compartment 10. The cap 17 includes a flat end wall 19 and an encircling skirt or flange 20 of proper shape and size to frictionally engage the open end of the wall 13. The cap 17 is usually cemented or otherwise affixed to the end of the wall 13 so as to form a permanent closure for this end of the device. The skirt or flange 20 is preferably of substantial thickness so as to project beyond the walls of the relatively slidable part 11 in the manner and for the reason which will be later set forth.

The part 11 of the device is usually provided with a bifurcated end designed to engage in the nostrils. The 60 part 11 includes a sleeve 21 as a relatively larger base portion of proper size to snugly fit about the container

wall 13 and to slide longitudinally relative thereto. A pair of rounded relatively small sleeves 22 and 23 having rounded extremities 24 and 25 project from the wall or sleeve 21. These sleeves 22 and 23 are hollow projections extending in substantially parallel relation from hollow oval part 11 and spaced apart in the direction of the major axis of oval part 11 and with opposed inner surfaces tapering slightly apart and outer surfaces tapering to a greater degree to provide extremities 24 and 25 terminating in apertures 26 and 27 respectively, which extremities are spaced properly to enter the nostrils. The sleeves are hollow and the rounded ends 24 and 25 thereof are provided with apertures 26 and 27 respectively which form a communication between the outside and the inside of these sleeves. As shown in Figures 2 and 3 of the drawings, the sleeves 22 and 23 are spaced and a partition wall 29 is provided between these projecting sleeves. The partition wall 29 is provided with a central tapered projecting plug 30 of proper shape and size to fit into the frusto-conical indentation 15. The conical projection 30 acts as a tapered valve and the frusto-conical wall 15 acts as a tapered valve seat. When the projection 30 is against the wall 15, the passage 16 is closed by the valve plug 30.

A pair or a series of opposed pockets 31 are provided in the outer surface of the wall 13 in spaced relation to the upper end of the cap flange 20. The inner surface of the telescoping wall 21 is provided with wedge shaped projections 32 which extend into the pockets 31. The projections 32 are tapered so as to slide over the wall 13 as the two parts are telescoped together, the member 21 being formed of a plastic material which is sufficiently resilient to flex or expand to the necessary degree. The butt ends of the projections 32 engage against a wall of their corresponding pockets to resist outward separation between the parts 10 and 11. Since the pockets 31 are of proper dimensions to permit a limited longitudinal movement of the projections therein, the parts 10 and 11 can move telescopically through a fixed distance.

Apertures 33 are provided through the wall 13 near the cap flange 20. These apertures are closed by the wall or sleeve 21 in one extreme position of the telescoping parts. The apertures are opened in the other extreme position of these parts. The parts 10 and 11 may be pulled completely apart if desired, but the engagement of the projections 32 in the pockets 31 definitely resists complete separation.

The pockets 31 are proportioned so that when the sleeve 21 is in closed position as shown in Figure 3 and is abutting the flange 20 of the cap, the plug 30 is in closed position to close the aperture 16. At this time the apertures 33 through the wall 13 are also closed. However, by pulling the parts 10 and 11 apart a short distance, the plug 30 is withdrawn from sealing position against the wall 15 surrounding the aperture 16 and the edge of the wall 21 is moved beyond the apertures 33, allowing these apertures to open.

The cap 12 is shaped to fit over the sleeves 22 and 23 so as to protect these sleeves from dust or dirt. The cap 12 includes a rounded closed end 34 which blends into an encircling flange or wall 35 which fits the shape or contour of the outer sides of the sleeves 22 and 23. Thus the cap 12 frictionally engages in place and may be removed when the device is to be used.

It is obvious that when the elements are in the contracted position shown in Figure 3, air is not allowed to either leave or enter the interior of the chamber 10, thereby preserving the medicament contained therein. When the two parts are moved longitudinally into the open position shown in Figure 2 of the drawings, the rounded ends of the sleeves 22 may be inserted into the nostrils

and air may be drawn into the interior of the compartment 10 through the inlet openings 33 and may be drawn into the sleeves 22 and 23 through the outlet port 16.

In accordance with the patent statutes, I have described the principles of construction and operation of my inhaler and while I have endeavored to set forth the best embodiment thereof, I desire to have it understood that obvious changes may be made within the scope of the following claims without departing from the spirit of my invention.

I claim:

1. An inhaler including two relatively telescoping parts comprising a hollow tubular container having end walls thereupon, the other of said parts having a wall embracing the tubular wall of said first part and slidably engaged thereupon, said other part merging into a pair of spaced nostril engaging sleeves each having a passage therethrough, the telescoped end of said first part having an indentation therein, and an opening therethrough, at the end of said indentation a partition wall connecting between said sleeves at the ends thereof remote from their nostril engaging portions, said partition wall carrying a valve portion engageable into said indentation to close said opening in one slidable position thereof, the tubular container wall having an opening therethrough enclosable by said embracing wall, slidable movement of said other part into one position serving to open both of said openings and to close both openings when moved into an opposite position.

2. An inhaler including a hollow body designed to contain a medicament, a pair of spaced hollow projections extending from said body in substantially parallel relation, said projections being spaced a distance proper to permit insertion into the spaced nostrils, the outer surfaces of said projections tapering inwardly throughout their length to provide a relatively small extremity and a relatively larger base telescopically connected to said hollow body, the interior of said projections being in communication with the interior of said hollow body, the extremities of said projections having apertures therethrough.

3. The structure described in claim 2 and including a valve member between said spaced projections and said body.

4. The structure defined in claim 2 and in which the projections include inner surfaces tapering apart, and outer surfaces tapering inwardly at a greater angle than the taper of the inner surfaces.

5. An inhaler including a hollow body of generally oval shape having a pair of projections extending in substantially parallel spaced relation therefrom spaced apart in the direction of the major axis of the oval, said projections having a slightly tapering inner opposed surfaces and outer surfaces tapering inwardly throughout their length to a greater degree, the projections terminating in end apertured rounded extremities.

6. The structure described in claim 5 and including an inner receptacle in telescoping relation to the hollow body and having an aperture therein communicating with the interior of said projections.

7. The structure described in claim 6 and including a valve projection between said spaced projections engageable into said aperture in said inner receptacle.
